FOLDING UMBRELLA

Filed April 16, 1928

FIG. 1

Inventor

ALLEN HARTMAN

By: Ben V. Zillman
Attorney

UNITED STATES PATENT OFFICE.

ALLEN HARTMAN, OF ST. LOUIS, MISSOURI.

FOLDING UMBRELLA.

Application filed April 16, 1928. Serial No. 270,175.

My invention relates to improvements in umbrellas, and more particularly to umbrellas so constructed that they may be folded or collapsed into a small, compact bundle 5 which may be placed into a trunk, suitcase or any other suitable place when not in use.

The invention has among its objects, the production of an umbrella of the kind described, which shall be simple in construction, sturdy, light, neat and attractive in appearance, easy and quick-acting in operation, without danger of getting the fingers caught in any of the operating parts, and efficient and satisfactory for use wherever 15 found applicable.

Many other objects and advantages of the construction herein shown and described, will be obvious to those skilled in the art to which this invention appertains, from the 20 disclosures herein given.

To this end, my invention consists in the novel arrangement, construction, and combination of parts herein shown and described, and uses mentioned, and more particularly pointed out in the claims.

In the drawings, wherein like reference characters indicate like or corresponding parts throughout the views,

Figure 1 is a longitudinal or vertical sectional view of my improved device, some of the parts being shown in elevation; and

Figure 2 is an enlarged detail view of the latch mechanism used.

In the drawings, wherein I have illustrated the preferred embodiment of my invention, there is shown an umbrella which may be used as the ordinary umbrella or parasol in the usual manner to protect the user from the elements, and when the need 35 for such protection has passed, it is possible to so fold or collapse the various parts making up the device so that the folded umbrella will occupy but a very small space as compared to the open or extended umbrella, and 40 permit of the folded umbrella being stored or placed in any suitable container, such as the hand-luggage, trunk, drawer, etc.

The cane portion of the umbrella is preferably made in two or more sections 1 and 2, 50 slideable one within the other so that they may be telescoped relative to one another as indicated in dotted lines in the drawing, or may be extended to the elongated positions indicated in heavy lines thereon. The 55 thinner cross-sectioned section of the handle

member 1, has the usual handle or grip element 3 fixed thereto at one end, this end being termed the lower end for the sake of convenience and clarity in this description. The section 1 is longitudinally slideable within the other section 2, there being means provided for preventing relative rotation between these sections during this sliding action, as for example by providing a guide or groove 4 in one of the said sections, as 60 for example the section 1, and a lug, pin or other projection 5 on the other cooperating section, this projection being struck up from the metal itself as shown, if so desired. In order to maintain these cane sections adjustably fixed in either the extended or telescoped relation, a suitable latch member 6 65 may be provided, as shown.

In Fig. 2, wherein the latch member is shown in enlarged detail, it will be noted 75 that the same comprises an element somewhat in a bell-crank lever shape, pivoted intermediate its ends upon a suitable pin or bearing 7; one end of the element being pointed with an inwardly directed pin 8 80 adapted to selectively engage in either of a pair of apertures or detents provided at the upper and lower ends of the slideable section, the other end of the element being provided with an enlargement or button 9. A 85 spring 10 may be provided so as to constantly urge said element into its detent-engaging position. The upper and lower detents or apertures on the cane section 1 are indicated at 11 and 12 respectively. 90

The relatively stationary section 2 of the cane member is provided with a disk 13 fixed thereto in any suitable manner, as by welding or the like, this disk being dished (with the convex surface uppermost) and is provided with a circumferentially arranged and spaced series of openings or apertures 14 adjacent the periphery thereof, said openings being radially elongated and of a width to slidably receive the cover-supporting ribs therethrough, as will be more clearly hereinafter described. 95

Slidably mounted upon the cane section 2 is a head block or sleeve member 15, said member preferably abutting against the disk 13 when at the uppermost point of its sliding travel. A pin 16 may be provided on the block to extend inwardly and be slidably received within a longitudinal slot or guide-way 17 provided through the wall of the 100 105 110

cane section 2, to prevent relative rotation between the block and said cane section and also to act as a limit stop in both directions of travel of the block.

5 A latch member 6 like that previously described between the cane sections, is provided between the cane section 2 and the slideable block 15, the pin portion 8 being selectively engageable within either of the apertures 18 10 and 19 provided adjacent the intermediate and lower end of the section 2, as shown.

A series of cover-supporting ribs or rib members R are hinged or pivoted at one end circumferentially spaced about the upper end of the block 15, the block having vertical cut-out portions 20 of a size to receive the adjacent portions of these ribs when the latter are in their folded positions, as will be hereinafter described. Each of these ribs 20 extends upwardly and outwardly from its hinged end, projecting slidably through an aperture or opening 14 of the cap or disk member 13 to a short distance therebeyond (when the umbrella is in the open position) 25 and is thence bent downwardly and outwardly away therefrom, the two divergent or angle-forming portions of the ribs being indicated as 21 and 22 respectively.

To the outer ends of the ribs R there are 30 hinged the auxiliary or cooperating rib sections R', the hinge being indicated at 23. When the umbrella is opened, the two cooperating rib sections form the full cover-supporting rib sections for the cover 24, said 35 cover being stitched or otherwise suitably secured at two or more points 25 and 26, to each rib section R', and if so desired the cover is free of securement to the rib sections or members R.

40 A series of stay rods or ribs S are arranged to cooperate with the cover-supporting ribs, each of the stay rods being hinged at one end adjacent to the lower end of the block as at 27, and hinged at its other end 45 intermediate the ends of the rib section R', as at 28.

When the umbrella is in its opened position, as indicated in the full lines of the drawing, the ribs R project through the 50 openings of the disk, the upper surface of the ribs engaging against the upper edge of the openings as shown. When the latches between the cane sections and the head block and one of the cane sections are released so 55 as to permit of the sliding movement of the sections and block, the ribs and rods will assume the position indicated in the dotted lines, whereby the rib sections R will have slidably moved inwardly and downwardly 60 through the openings through the disk, with the portion 21 of the ribs lying within the vertical recesses 20 of the block, and the rib sections R' overhanging the edge of the disk and extending substantially parallel to the 65 center line or axis of the umbrella.

In the collapsed or folded position, the umbrella has a very much reduced overall length and the width or cross-section size thereof has been increased but slightly. In such a folded position, it is relatively compact and may be stored out of the way until again needed, and in any number of suitable places and may be easily carried in any suitable container when traveling. The opening and closing of the umbrella is simple, quick 70 and easy, and the cost of construction of an umbrella embodying my invention is but little, if any, greater than the present cost of the non-collapsible type.

Having thus described my invention, it is 80 obvious that various immaterial modifications may be made in the same without departing from the spirit of my invention; hence I do not wish to be limited to the exact form, arrangement, construction and combination of parts herein shown and described, except as limited by the claims.

What I claim as new and desire to secure by Letters Patent is:—

1. A folding umbrella, comprising a cane, 90 a head block slideable thereon, cover-supporting ribs pivoted to said block, and stay rods pivotally connected at one end to said block and at their other end to said ribs.

2. A folding umbrella, comprising a telescopic cane member having an enlarged disk at one end and a handle at the other end, a sleeve slidably mounted on said cane member, cover-supporting ribs slidably extended through said disk and pivoted at one 100 end to said sleeve, and stay rods pivoted to said sleeve and to said first-mentioned ribs.

3. A folding umbrella, comprising a plurality of slidably telescoping cane sections, a head block slideable on one of said sections, a 105 plurality of cover-supporting rib sections pivoted at one of their ends to said block, a second series of rib sections each hinged at one end to a first-mentioned rib section, and stay rods hinged to said second-mentioned 110 rib sections and said block at their opposite ends.

4. A folding umbrella, comprising a plurality of slidably telescoping cane sections, and enlarged disk fixed to one end thereof, 115 a head block slideable on one of said sections, a plurality of rib sections slidably extended through said disk and pivoted at one end to said block, a second series of rib sections hinged at one end to the other end of the 120 first-mentioned ribs, and stay rods hinged at one end to said block and hinged at their other end intermediate the ends of the ribs of the second-mentioned series.

5. A folding umbrella, comprising a telescopic cane member having an enlarged disk at one end, provided with openings in a circumferentially spaced series therethrough, a sleeve slidably on said cane member, cover-supporting ribs hinged at one end to said 130

sleeve and bent intermediate their ends so as to extend slidably through the openings upwardly and outwardly and thence extend downwardly and outwardly, a second series 5 of ribs hinged to the outer ends of said first-mentioned ribs, and stay rods hinged at one end to said sleeve and at their other end to the ribs of the second series intermediate the ends thereof.

10 6. An umbrella comprising a handle, a

sleeve slidably mounted thereon, rib members having pivotal connection with the sleeve to fold against the handle, rib sections pivotally mounted upon the rib members, and means establishing connection between 15 the sleeve and rib members to dispose the rib members and rib sections in end to end relation.

ALLEN HARTMAN.
